[57] **ABSTRACT**

Aliphatic hydrocarbons of from four to six carbon atoms are dehydrogenated by passing the hydrocarbons and chlorine through a reaction zone containing a catalyst of iron phosphates of group IIA metals, optionally promoted with a minor amount of chromia, at a temperature of from 450° to 675° C.

8 Claims, No Drawings

CHLORINATIVE DEHYDROGENATION OF HYDROCARBONS

BACKGROUND OF THE INVENTION

This invention relates to the gas-phase dehydrogenation of hydrocarbons to the corresponding olefins, diolefins, acetylenes or triolefins.

In the production of unsaturated hydrocarbons, useful as polymerizable monomers in the manufacture of plastics and elastomers, a number of processes have been employed. One such process employs a suitable catalyst to convert a substantial proportion of a principally paraffinic feed to the corresponding mono-olefins, with hydrogen as a by-product. Oxidative dehydrogenation processes utilize oxygen in the feed, and yield water vapor as a by-product. The inclusion of halogen, along with oxygen, in the feed has also been disclosed.

In all of these known processes a principal aim is to obtain as high as possible conversion of the feed material, with a maximum proportion of the effluent appearing as the desired unsaturated hydrocarbons, and a minimum amount of unwanted by-products. Thus a need exists for a system which would produce a high conversion of the saturated starting materials, with a correspondingly high selectivity to olefinic or diolefinic products. Selection of the combination of a process and a catalyst system which act together to produce optimum results is of prime importance to investigators in the field of petrochemicals.

SUMMARY OF THE INVENTION

The process of the invention presents a means for dehydrogenating hydrocarbons with improved conversion and selectivity to the desired unsaturated hydrocarbons.

In essence, the invention is carried out by passing a mixture of the hydrocarbon feed, together with from 0.1 to 2.0 moles of chlorine per mole of hydrocarbon at a temperature of from about 450° to about 675° C. in contact with a catalyst of iron phosphates of group IIA metals, to obtain the corresponding hydrocarbon having the same number of carbon atoms and a greater degree of unsaturation. The catalyst can optionally be promoted with minor amounts of chromia to aid in coke removal.

The hydrocarbon feed material of the invention is selected from straight chain or branched chain paraffins of from four to six carbon atoms, monoolefins or diolefins of from four to six carbon atoms, or mixtures thereof. Examples of feed materials are n-butane, n-pentane, n-hexane, isobutane, methyl butane, butene-1, cis-butene-2, trans-butene-2, 2-methyl-butene-3, 2-methyl-butene-1 and mixtures thereof. Refinery by-products consisting of a mixture of four-carbon compounds are a typical feed stock.

The chlorine fed into the reaction will react primarily to give HCl, and will also produce various chlorinated hydrocarbons, to a lesser degree. The reaction is designed to produce unsaturated hydrocarbons, principally, and the production of chlorinated hydrocarbons is desirably kept to a minimum. The amount of chlorine used can vary from 0.1 to 2.0 moles of chlorine per mole of hydrocarbon feed, and will preferably be from about 0.5 moles to 1.5 moles per mole of hydrocarbon. In general, higher ratios of

chlorine will produce a greater degree of unsaturation in the products, but may also produce an increased amount of chlorinated hydrocarbons.

A diluent material can also be used such as nitrogen or steam, or both. Air may be employed as a partial source of diluent, although the process works well in the absence of oxygen. Steam is especially advantageous, as it may be easily condensed out of the product stream. From about five to about 35 moles of steam per mole of feed hydrocarbon can be used advantageously. The use of from zero to about four moles of nitrogen per mole of hydrocarbon feed may be desirable from a handling standpoint, but is not essential to the process.

The reaction zone may be of any convenient design which gives good contact between the catalyst and the gaseous mixture passing advantageously employed.

The catalyst of the invention is essentially a mixed phosphate of iron and a metal from group IIA, prepared in any convenient manner. Although the relative proportions of the metals do not appear to be critical, an atomic ratio of group IIA metal to iron ranging from 7.5 to 9.2 is found to be most effective. In general, the catalyst can be readily prepared by co-precipitating soluble iron and group IIA metal salts, washing the precipitate to remove remaining soluble materials, and drying the precipitate to constant weight. The dried catalyst can be prepared in pellet form or ground to any desired particle size for use in fixed-bed or fluid-bed reactors.

Optionally, a minor amount of chromia can be added to the catalyst before drying. It has been found that the presence of this minor amount of chromia aids in removing coke from the catalyst during the regeneration process. Regeneration is advantageously accomplished by passing air or oxygen, mixed with steam, over the catalyst at normal operating temperatures (as defined below).

In operation, the mixture of feed hydrocarbons, chlorine, and optionally diluent materials can be passed through a pre-heating manifold in which the mixture is raised to a preheat temperature of from 200° to 300° C. This step is not essential, but is helpful in that the reactants arrive at the reaction zone at a temperature close to that employed in the zone itself, and the reaction temperature can be better controlled.

The preferred temperature of the invention for the reaction zone is from about 450° C. to about 675° C., and the reactor can be jacketed to provide for heat input or removal to maintain this optimum range.

The effluent gas leaving the reaction zone is treated to separate it into its components. Water vapor is condensed out by cooling, and the unreacted chlorine and by-product HCl are recovered. The chlorine can be recycled, and the HCl can be oxidized to chlorine, which in turn can also be recycled into the reaction zone. The remaining gaseous products can be separated by fractionation if desired, or further processed in their mixed state.

The unsaturated hydrocarbon products of the invention find many uses as chemical intermediates or as polymerization monomers. By-product materials can be re-cycled, or recovered and used. The chlorinated hydrocarbons, while not the desired products of this invention, may also be used as polymerization monomers

or chemical intermediates, with or without separating the mixture of chlorinated hydrocarbons into its components.

For convenience, the process can be operated at approximately atmospheric pressure, although higher or lower pressures can be employed if desired.

SPECIFIC EMBODIMENTS OF THE INVENTION

In order to illustrate the practice of the invention the following examples are supplied. Unless otherwise specified, all percentages and parts are by weight.

EXAMPLE I

A catalyst for use in the process of the invention was prepared in the following manner:

Two hundred and fifty-eight milliliters of 30 percent aqueous ammonia were diluted with 250 ml of water and added to a mixture of 136.8 g of 85 percent phosphoric acid and 400 ml of ice and water. To this solution was added slowly with stirring a solution of 325 g of magnesium chloride hexahydrate and 32.4 g of ferric chloride in 400 ml of water, causing precipitation of the magnesium-iron phosphate. During the above addition small amounts of 30 percent aqueous ammonia were added periodically in order to maintain the reaction mixture at pH 8. Stirring was continued 0.5 hr. after addition of the chloride solutions was complete. The precipitate was collected by filtration, re-slurried with water and filtered. The re-slurrying was repeated until the precipitate was free of chloride ion as determined by addition of silver nitrate solution to the filtrate. During the final re-slurrying 3.8 g of chromium oxide was added to the slurry. The filter cake was air dried overnight and then dried to constant weight in an oven at 140°C. Weight of the dried catalyst was 166.0 g. The quantities of reagents used were chosen to give an atomic Mg:Fe ratio of 8.2. The catalyst was ground to a particle size of 10 — 20 mesh.

EXAMPLE II

In a similar manner as Example I, a second catalyst was prepared. Two hundred and fifty-eight milliliters of 30 percent aqueous ammonia were diluted with 250 ml

of water and added to a mixture of 136.8 g of 85 percent phosphoric acid and 250 ml of water. To this solution was added slowly with stirring a solution of 235.8 g of calcium chloride dihydrate and 32.4 g of ferric chloride in 600 ml of water, causing precipitation of the calcium-iron phosphate. During the above addition small amounts of 30 percent aqueous ammonia were added periodically in order to maintain the reaction mixture at pH 8. Stirring was continued 0.5 hr. after addition of the chloride solutions was complete. The precipitate was collected by filtration, re-slurried with water and filtered. The re-slurrying was repeated until the precipitate was free of chloride ion as determined by addition of silver nitrate solution to the filtrate. During the final re-slurrying 4.4 g of chromium oxide was added to the slurry. The catalyst filter cake was air dried overnight and then dried to constant weight in an oven at 140°C. The length of the drying period is not critical. Weight of the dried catalyst was 129.8 g. The quantities of reagents used were chosen to give an atomic Ca:Fe ratio of 8.2. The catalyst was ground as in Example I.

EXAMPLE III

A series of trials was performed employing a heated tubular reactor, with silica pellets, and the catalysts of Examples I and II in a fixed reaction bed, as well as with an empty reactor. Analysis of the product was made with an in-line gas chromatograph. The incoming gases were preheated to 200° — 300°C., and the reactor was maintained at an average temperature of about 550°C. throughout the trials. Proportions of the various incoming and effluent gases are expressed as relative gaseous hourly space velocities (GHSV), defined as the volumes of material passed through the reactor (corrected to standard temperature and pressure) per hour, divided by the volume of the reactor. The differing GHSV's reflect the use of different reactor volumes; the flow of the feed hydrocarbon material (butane) was essentially the same in all runs. Pressure in the reactor was atmospheric, or slightly above. Measurements are summarized in the following table, showing improved selectivity to butenes and butadiene (BD), and reduced amounts of chlorinated products with the catalysts of the invention.

Run No.	Butane	Air	N ₂	Cl ₂	Steam	G.H.S.V.		Selectivity				Tar formation
						Conversion	Butenes	BD	Total			
Empty reactor:

We claim:

1. A process for dehydrogenating aliphatic hydrocarbons of from four to six carbon atoms which comprises contacting a mixture of the hydrocarbons and chlorine with a catalyst of iron phosphates of group IIA metals wherein the atomic ratio of group IIA metals to iron in said catalyst is from 7.5 to 9.2 atoms of group IIA metals per atom of iron at a temperature of from 450° to 675°C.

2. The process of claim 1, wherein the catalyst is promoted with a minor amount of chromia.

3. The process of claim 1, wherein the group IIA metal is calcium.

4. The process of claim 1, wherein the group IIA metal is magnesium.

5. The process of claim 1, wherein the aliphatic hydrocarbons consist essentially of butanes or pentanes.

6. The process of claim 1, wherein the molar ratio of chlorine to hydrocarbons is from 0.1 to 2.0 moles of chlorine per mole of hydrocarbons.

7. The process of claim 1, wherein an inert diluent is added to the mixture of chlorine and hydrocarbons.

8. The process of claim 3, wherein the inert diluent is steam, or nitrogen, or mixtures of these materials.
